HYDRAULIC DESCALER

Frank G. Cizek, Cincinnati, Ohio, assignor to American Steel Foundries, Chicago, Ill., a corporation of New Jersey

Filed May 9, 1956, Ser. No. 583,882

9 Claims. (Cl. 29—81)

This invention relates to a self-contained portable type apparatus for removing, by means of high pressure water spray, surface scale from heated billets which are to be subsequently forged.

The high pressure water spray process for removing scale from heated billets prior to the forging thereof is the fastest and most efficient descaling method known. In this process the preheated billet is passed at a predetermined rate through a controlled spray of high pressure water. The force of the impinging water first contracts and breaks the scale and then washes the loosened scale from the surface of the billet. A surface is thereby produced which requires no subsequent sand blasting for removal of scale. The advantages of this method are low operating costs and a greatly increased life of the forging dies when the descaled billet is subsequently forged.

Most of the existing descaling equipment is large and cumbersome and therefore necessarily fixed in location. This results in excessive handling and transporting of billets to the various forging hammers with consequent heat losses in the billets prior to forging. Portable descaling machines currently on the market have several disadvantages including: First, accommodation of only a small range of billet diameters unless parts of the machine are changed, and second, the utilization of a combined water-oil system with the consequent danger of contamination, through leakage, of one of the fluids by mixture with the other fluid.

One of the objects of this invention is to provide a descaling device which is completely portable thereby eliminating the necessity of multiple handling of billets and the transporting of billets from the descaler to the hammer or forging press.

Another object of the invention is to provide a descaling apparatus having equalized water spray distribution through novel one-way nozzles.

Another object of the invention is the provision of adjustable nozzles wherein the water spray can be directed more effectively on unsymmetrical objects.

Another object of the invention is to provide a portable descaler wherein the spray water system and the cylinder actuating oil system are completely separate thereby negating any co-mingling of oil and water.

It is also an object of this invention to provide a portable descaling machine which is adapted to accommodate a large range of billet diameters without the necessity of interchanging parts of the machine.

Still another object of the invention is to provide a water system for a portable descaler which includes means to prevent water draining from the system between descaling cycles.

These objects together with other objects and advantages will be apparent from the following specification and drawings, in which:

Figure 1 is a side elevational view of the portable descaler;

Figure 2 is a top plan view of the device shown in Figure 1;

2

Figure 3 is a partial front view of the descaler showing more clearly the spray nozzle ring and the adjusting means therefor;

Figure 4 is an enlarged fragmentary perspective view 5 of the descaling portion of the machine;

Figure 5 is a longitudinal section through a spray nozzle;

Figure 6 is a diagram of the hydraulic system of the device, and

10 Figure 7 is an electrical wiring diagram for the apparatus.

Referring to the drawings, it will be seen that the machine comprises a frame 10 which supports on the lower portion thereof the control and power components 15 which are indicated generally at 12 and a sump and scale basket indicated at 13. The frame supports on the upper portion thereof the descaling section which is indicated generally at 14 and the power cylinder section which is indicated generally at 16.

20 The descaling section 14, the internal construction of which is shown in Figures 3 and 4, comprises a cabinet 18 (Figure 4), the sides of which are formed of swinging doors 20 which are counterweighted as at 22 for a purpose to be described hereinafter. Centrally of the cabinet 25 18 is a V-shaped trough 24 adapted to support the billet (not shown) which is to be descaled.

The machine may be loaded from the front where an adjustable billet receiving tray 25 (Figures 1 and 2) is provided or, alternately, the machine may be loaded from 30 either side by means of an inclined loading chute 26 (Figures 2 and 4) which is provided with conventional screw type adjustments generally indicated at 28. The loading chute in the illustrated embodiment comprises a frame 27 having slide bars 29 mounted thereon. The 35 frame 27 is supported at its inner end by the cabinet 18 and is supported at its outer end by the adjustment means 28. The angle of the loading chute and the position of the counterweights 22 on threaded studs 31 are regulated so that when a billet is placed on the side loading chute, it will roll toward the cabinet and bump the door with sufficient force to cause the door to open, aided by the counterweights, and roll down into the V-shaped trough 24 at which time the door will automatically swing to its closed position.

40 At the extreme end of the machine, there is an adjustable hollow spray ring 30 (Figure 3) which is provided with a plurality of spray nozzles 32 of which there preferably would be either four or eight for round, square and hexagonal bars. Odd shaped pieces may require a special pattern. The spray ring is in the form of a hollow

50 annulus so that when the ring is centered around the billet, all of the spray nozzles are uniformly spaced from the peripheral surface of the billet. Mounted on the frame is a flanged guide member 34 which extends across the top and along the sides of the ring 30, as best seen in 55 Figure 3, and holds the spray ring in fixed position laterally but permits movement of the spray ring upwardly or downwardly so that the ring may be adjusted with its axis coaxial with the axes of billets of differing diameters.

60 A pair of lugs 35 extend outwardly of the spray ring through slots (not shown) in the member 34 and rotatably receive threaded rods 36 which extend upwardly from the lugs, as best seen in Figure 3, and are threadably received through fixed nuts 38 which are secured to the flange 34. One of the threaded rods 36 is provided 65 at its upper end with a sprocket 40 which is interconnected by means of a chain 42 to a sprocket 44 secured to the upper end of the other threaded rod 36. An adjusting handle 46 is secured to or formed integrally with the sprocket 44 so that rotation of the handle will cause both sprockets and both adjusting rods to rotate simultaneously. Depending on the direction of rotation, the

threaded rods will be moved upwardly or downwardly because of their threaded engagement with the fixed nuts 38, and this upward or downward movement will be transmitted to the lugs 35 and consequently to the nozzle carrying ring 30. In this manner, the nozzles may be spaced evenly from a billet regardless of the diameter of the billet, and uniform descaling will result without excessive cooling of any portion of the billet which would occur if the ring were not centered about the billet. By inserting an adapter 31 (Figure 6) between any of the nozzles 32 and the spray ring 30, both the spray angle of the nozzles and also the distance of the nozzles from the spray ring may be varied. This feature, together with the earlier mentioned feature of possible variation of the number and peripheral location of the spray nozzles, permits adaptation of the spray pattern to de-scale irregularly shaped billets effectively.

Referring again to Figures 3 and 4, it is seen that a pusher head 48 is provided which is generally conical in shape and is formed in a series of steps 39 of decreasing diameter toward the apex of the cone. This conical stepped contour has the effect of deflecting the water spray against the trailing end of the billet as it passes through the spray ring thereby assuring complete descaling of the entire billet. It should be noted that the stepped cone will accommodate the complete range of diameters of billets which may be descaled in the machine. The pusher head 48 is secured to the end of a piston rod 50 (Figures 1, 2 and 6) which is in turn secured to a piston 52 (Figure 6) reciprocable in an oil cylinder 54. Extending from the side of the piston opposite the piston rod 50 is another piston rod 56 which extends outwardly of the oil cylinder 54 and is secured to a transverse yoke 58. The yoke 58 also carries for movement therewith rams 60 received within a pair of water cylinders 62—62, respectively. It will be understood that suitable packing is provided in all of the cylinders, even though the packing is not shown in the drawings. Although two water cylinders are shown in this embodiment and are preferable in order to obtain equal water distribution and a balanced load on the yoke, in some embodiments one water cylinder may be utilized instead of two.

Referring to Figure 6, it is seen that water is fed into the system from a customer's supply line 72 through a shut off valve 74 and a check valve 76 and thence through lines 78 and 80 and to the water cylinders 62. The water of the customer is generally city water at approximately forty pounds pressure, and this pressure is enough to overcome the resistance of the check valve 76 which is provided in the line to prevent forceful expulsion of water from the system and back into the city line during the descaling portion of the cycle with the possibility of contaminating the water supply.

Prior to the beginning of a cycle, oil is circulated from a pump 82 through a four-way valve 84 and thence through line 86 and line 88 into the low pressure side 89 of the oil cylinder 54. The pressure is kept low by means of a regulator valve 90 which by-passes the circulated oil at a predetermined pressure and returns surplus oil to a reservoir 92. The combined pressures of the low pressure oil and the water supply urge the rams 60, the piston 52 and the pusher head 48 rearwardly to the return end of the stroke at which time a limit switch 94 will be closed for a purpose to be explained hereinafter in conjunction with the operating cycle. It should also be understood that the force of the oil, which is urging the oil piston rearwardly, is preferably less than the force of the water urging the rams 62 rearwardly. If this were not so, the rams would be forced rearwardly at a faster rate than the lines 78 and 80 and the water cylinders 62 could be filled with water and as a consequence, air might be drawn into these lines through the spray nozzles. Action of this type might possibly result in poor descaling because during the descaling portion of the cycle the air pockets in lines 96 would prevent the proper amount of

water for descaling from being delivered through the nozzles.

In the descaling portion of the cycle, which will also be described hereinafter in greater detail, high pressure oil is delivered to the high pressure side 53 of the oil cylinder 54 thereby driving the piston 52 and the pusher head 48 forward at a predetermined rate of speed. The pusher head in turn drives the heated billet out of the cabinet through the descaling spray system. As the piston 52 moves forward, the rams 60 will also move forwardly, inasmuch as they are secured to the same yoke and are movable therewith. The water, therefore, which had filled the water cylinders 62 is now forced at high pressure through the lines 96, through the spray ring 30, and thence through the nozzles 32 and onto the billet. It will be understood that the rate of speed at which the billet is moved through the spray and the quantity of water which is sprayed onto the billet can be correlated to any desired relationship so that the proper descaling action will occur with the least amount of water and consequently the smallest cooling effect on the billet. A one-way check valve 98 is inserted in each of the lines 96 as close to the spray ring as possible to aid in preventing water from draining from the system between descaling cycles or from being sucked back into the water cylinders on the return stroke thereof. These valves are, of course, set at a pressure higher than the pressure setting of check valve 76 and the pressure of the source 72.

In utilizing separate water and oil cylinders, with the oil cylinder having a piston secured to and movable with the pusher head, and each of the cylinders having a piston secured to and movable with a common yoke, it is possible to accurately control the quantity of water discharged from the nozzle for each increment of movement of the pusher head. This, as mentioned heretofore, results in uniform water coverage on the billet and complete descaling with minimum cooling. This important result is attained without any danger of water leaking into the oil system or oil leaking into the water system. Where a unitary oil-water cylinder is used, the eventual wear of the packing material results in undesirable co-mingling of the two fluids.

The spray nozzle assembly which is utilized in the descaling machine is illustrated in Figure 5 and comprises a hollow body 200 which is threaded as at 202 to receive a threaded nut 204 by means of which the nozzle 206 may be releasably secured to the body. A helical coil spring 208 urges a ball 210 against a tapered seat 212 to prevent flow of water through the nozzle at low pressures. This type of construction aids in keeping the lines full of water which will be immediately available during the descaling portion of the cycle. Positioned between the nozzle 206 and the ball 210 and disposed internally of the spring 208 is a hollow stop member 214 which is provided with a plurality of ports 216. In order to minimize spring failures due to the high water pressure exerting a sufficient force on the ball 210 during the descaling portion of the cycle to compress the spring solid, a stop 214 is utilized. The stop prevents the spring from closing off flow to the orifice. By inserting the stop 214 in the assembly and making the height of the stop greater than the solid compressed height of the spring, the spring compresses a sufficient amount to permit flow past the ball but is restrained from compressing solidly and then being twisted and distorted as the high pressure water forced its way through the solid spring. Water flow is thereby permitted between the coils of the spring and through the ports 216 in the stop member 214 and thence through the orifice of the nozzle. The spring, therefore, is never overstressed or distorted, and spring failures are reduced to a minimum.

Describing now an operating cycle of the device and referring to Figures 6 and 7, it should be recalled that the descaling machine can be loaded from the front or

from either side. Side loading shall be considered first. In side loading, the operator first depresses a motor start switch 113 thereby completing a circuit to energize the coil of a relay 119 to start the motor 83 and also completing a circuit to close normally open contacts 118 to hold the motor circuit closed after the operator releases the switch 113. The operator then momentarily depresses a normally open switch 101 which completes a circuit through normally closed contacts 106, of a switch 104 in side loading position thereof, switch 101 and normally closed contacts 166 to energize the coil of a control relay 100 thereby closing the contacts 102 and 112 of the relay 100. Closing contacts 102 holds the circuit through the relay 100 after the operator releases the normally open switch 101. The billet is then placed on the loading chute 106 and its weight causes it to open one of the doors 20 on the side of the cabinet 18. The door, when opening, closes contacts 114 and 116 and opens contacts 115 and 117, these contacts being in limit switches conveniently located on the cabinet 18 for actuation by the door. If at this time the rams 60 and the yoke 58 are not in their extreme rearward position, nothing further will happen. However, if the rams are in the proper position, the limit switch 94 will be closed by bracket 164 extending from the yoke 58 and a circuit will be completed through contacts 94, normally closed contacts 108 of the selector switch 104, contacts 112 and contacts 116 to energize the coil of a control relay 120. Energization of this coil closes contacts 122, 126 and 134 of the relay 120, the contacts 122 acting to hold the circuit through the relay 120, even when contacts 112, 114 and 116 are opened as will be explained hereinafter. When the billet drops into its proper position on the V-shaped trough 24, the door will overcome counterweights 22 and will swing closed. The closing of the door causes contacts 114 and 116 to open and also causes contacts 115 and 117 to close. At this time a circuit is completed through the contacts of switch 94, the contacts 126 of relay 120, the closed limit switch contacts 115 and 117 and the normally closed contacts of limit switch 128 to energize the coil of a control relay 130. Energization of this coil opens normally closed contacts 166 to de-energize the coil of relay 100 and also closes the normally open contacts 132 to complete a holding circuit for relay 130. Energization of relay 130 also closes normally open contacts 142 and 144 of the relay 130 to complete a circuit through a solenoid air operated valve 148 (Figures 6 and 7) which causes the spindle of the valve to shift to admit air from a conventional source (not shown) to an air cylinder 146 (Figure 6) which is interconnected with the four-way valve 84 in such a manner that high pressure fluid will now be directed from the entry port 160 through line 162 and into the high pressure side 53 of the oil cylinder 54. This action will drive the piston 52, together with the pusher head 48, forward to push the billet through the spray ring and out of the cabinet. Simultaneously with this action, the rams 60, moving with the ram 56 through their mutual connection to the yoke 58, will be moved forwardly and will urge the water which had been stored in front of the rams 62 through the spray nozzles at a predetermined rate to accomplish the descaling of the billet. A relief valve 150 is utilized in parallel with the high pressure line 151 leading from the pump to the high pressure side of the oil cylinder to prevent overloads on the system if some part of the system should become clogged with foreign material.

When the pusher head and rams reach the predetermined end of the stroke, bracket 164 strikes the reversing switch 136 (Figure 6) causing the contacts 137 (Figure 7) of the switch to close and the contacts 128 of the switch to open. Closing contacts 137 energizes the coil of a control relay 138 causing the normally closed contacts 170 to open thereby de-energizing the coil of the control relay 130. De-energization of the coil of the

relay 130 opens contacts 142 and 144 of this relay and de-energizes thereby the coil of the solenoid operated air valve 148. Deenergization of the solenoid operated air valve 148 reverses the port opening of the air cylinder 146 which operates to close the high pressure outlet ports of the four-way valve 84 leading to the oil cylinder 54 and to open the port to the low pressure side of the oil system as described heretofore thereby permitting the low pressure oil and the pressure of the water from the supply line to return the piston and the rams to the starting position whereupon the cycle will be completed. De-energization of the coil of relay 130 also causes contacts 166 to close. Energizing the coil of the relay 138 also closes the contacts 140 of relay 138 to provide a holding circuit through these contacts. De-energizing relay 100, as explained above, causes contacts 122 to open thereby de-energizing the coil of relay 120. At the extreme end of the return stroke, the bracket 164 once again strikes the limit switch 94 which breaks the circuit through the coil 20 of relay 138 at which time the cycle is ready to be repeated.

When it is desired to load the descaling machine from the front, the operator first pushes the switch 104 which operates to close contacts 110 and to open contacts 106 and 108 of the selector switch, inasmuch as the portions of the circuit which are controlled by contacts 106 and 108 are not required when loading from the front. A billet is then pushed into the cabinet from the front until it strikes a swinging lever 180 (Figure 6) which is pivotally supported from the pusher head 48. The lever 180 is operatively engageable with a push rod 182 to which is secured a contact sleeve 184. When the billet strikes the lever 180, the contact sleeve, acting against the pressure of a return spring 186, trips a limit switch 124 and completes a circuit through contacts 110, switch 124, the normally closed contacts 128 of limit switch 136 and normally closed contacts 170 to energize the coil of the control relay 130. Energization of relay 130 closes the contacts 142 and 144 thereof and completes a circuit to energize the solenoid air operated valve 148 in the same manner as described relative to side loading. The remaining part of the cycle is identical with that which has been described heretofore for side loading of the descaler.

I claim:

45 1. In a device for removing scale from the surface of a heated billet, the combination of means for supporting the billet, spray means, fluid lines connected to said spray means for conveying water thereto, and means to move the billet through said spray means and simultaneously feed water under high pressure through said lines and said spray means, said moving means comprising a hydraulic cylinder having a piston therein dividing the cylinder into a high pressure chamber and a low pressure chamber, a piston rod extending from the low pressure chamber of the cylinder and being directly engageable with said billet to move the billet through the spray means during the high pressure stroke of the piston, a second piston rod extending from the high pressure chamber of the cylinder, at least one water cylinder connected to said lines, an operating ram carried in said water cylinder, and a yoke secured to said piston rod and said ram for unitary movement therewith, said spray means being automatically responsive to movement of said first mentioned piston rod, said second piston rod, said ram, and said yoke.

2. In a device for removing scale from the surface of a heated billet, the combination of means for supporting the billet, spray means, fluid lines connected to said spray means for conveying water thereto, and means to move the billet through said spray means and simultaneously feed water under high pressure through said lines and through said spray means, said last mentioned means comprising a pusher head engageable with said billet, a fluid actuated piston, said piston being operatively con-

nected to said pusher head for imparting reciprocal movement thereto, a source of high pressure fluid for operating said piston, a pair of water cylinders, said water cylinders being connected to said fluid lines for delivering water therethrough under pressure, and ram means in said water cylinders, said ram means being operatively connected to said piston for movement therewith, said spray means being instantly responsive to each increment of movement of moving means.

3. In a hydraulic device for removing scale from the surface of a heated billet, the combination of a spray ring adapted to receive a billet therethrough, at least one water cylinder having ram means therein, a source of water to fill said cylinder on the return stroke of said ram means, a line from said cylinder to said ring for conveying water to said ring during the advance stroke of said ram means, an oil cylinder having a piston dividing said cylinder into advance and return chambers, means to supply oil at high pressure to said advance chamber, and a yoke operatively connected to said piston for movement therewith, said yoke having an operative connection to said ram means, said yoke, ram, and piston coacting in the same direction.

4. In a hydraulic device for removing scale from the surface of a heated billet, the combination of a spray ring adapted to receive a billet therethrough, a pair of water cylinders having ram means therein, a source of water to fill said cylinders on the return stroke of said ram means, fluid lines for conveying said water from said cylinders to said ring during the advance stroke of said ram means, an oil cylinder having a piston dividing said cylinder into advance and return chambers, means to supply oil at high pressure to said advance chambers, means responsive to the advance stroke of said piston to impart concurrent advance stroke motion to said ram means, and a pusher head for moving the billet through the spray ring on the advance stroke of the piston, said pusher head being directly connected to said piston for movement therewith.

5. In a hydraulic device for removing scale from the surface of a heated billet, the combination of spray means adapted to receive a billet therethrough, said spray means comprising an annular movable member, a plurality of nozzles carried by said member, and check means in said nozzles accommodating one-way flow of water therethrough, said check means comprising a seat, a ball movable toward and away from said seat, resilient means urging said ball toward said seat, and stop means to limit the movement of said ball away from said seat, a pair of water cylinders having ram means therein, a source of water to feed said cylinders on the return stroke of said ram means, fluid lines connecting said cylinders to said nozzles for conveying water to said nozzles during the advance stroke of the ram means, an oil cylinder having a piston dividing said cylinder into advance and return chambers, other fluid lines to supply oil at high pressure to said advance chamber, and means to impart advance stroke motion to said ram means, said last mentioned means being instantaneously responsive to the advance stroke of said piston.

6. In a device for removing scale from the surface of heated billets; the combination of means for supporting the billets; spray means to impinge a spray of water on the periphery of the billets as the billets are moved therethrough, said spray means comprising a hollow ring, said hollow ring being adjustably movable, and a plurality of spray nozzles carried by said ring, said hollow ring and spray nozzles being adjustably movable to provide equalized spray on the surface of said billets, regardless of the cross-sectional contour of the billets being descaled; and means to move said billets through said spray means at a constant rate, said spray means being responsive

to each increment of movement of said moving means.

7. A descaler comprising an hydraulic cylinder with advance and return chambers, another hydraulic cylinder with a return chamber, pistons in respective chambers, means mechanically interconnecting said pistons externally of said chambers, a source of pressure water connected to the return chamber of said other cylinder, means to direct spray on a work piece and having check valve means adapted to open at a pressure value greater than that supplied by said source, and means for delivering pressure fluid to said advance chamber to expel water from said last-mentioned return chamber at a value sufficient to open said valve means and spray a work piece, and means connected to the piston in said first-mentioned cylinder for moving a workpiece past said nozzle, said delivering means in return position delivering the related fluid to the first-mentioned return chamber at a value to produce return force on the related piston less than that produced by the water source acting against the related piston.

8. In a hydraulic device for removing scale from the surface of a heated billet, the combination of a spray ring adapted to receive a billet therethrough, at least one water cylinder having ram means therein, a source of water to fill said cylinder on the return stroke of said ram means, a line from said cylinder to said ring for conveying water to said ring during the advance stroke of said ram means, an oil cylinder spaced from the water cylinder and having a piston dividing said cylinder into advance and return chambers, means to supply oil at high pressure to said advance chamber, and means to impart advance stroke motion to said ram means, said means being disposed externally of said cylinder and being responsive to the advance stroke of said piston.

9. In a device for removing scale from the surface of a heated billet, the combination of: a fluid container, a spray device connected by a fluid line to said container, means for forcing fluid under pressure from said container to said spray means, a hydraulic cylinder, piston means reciprocal in said cylinder and connected to said force means for actuation thereof, means for supplying fluid of a different character to said cylinder to actuate said piston means on a forward and a return stroke, a source of said first mentioned fluid for delivering the latter to said container at a certain pressure value, and means for maintaining the force exerted on said piston means by said second mentioned fluid at a lower value than the force developed by said source against said expelling means whereby instantaneous operation of said spray device is afforded open actuation of said piston means on the forward stroke thereof.
